UNITED STATES PATENT OFFICE.

WILLIAM L. MCGRATH, OF ELMIRA, NEW YORK, ASSIGNEE TO ECLIPSE MACHINE COMPANY, OF ELMIRA, NEW YORK, A CORPORATION OF NEW YORK.

ENGINE STARTER.

Application filed September 17, 1920. Serial No. 410,932.

To all whom it may concern:

Be it known that I, WILLIAM L. MCGRATH, a citizen of the United States, residing at Elmira, in the county of Chemung and State 5 of New York, have invented certain new and useful Improvements in Engine Starters, of which the following is a specification.

My invention relates to engine starters and to that part thereof known as the drive 10 or transmission. The object of my invention is to provide a simple, efficient and reliable drive of economical construction and novel mode of operation as will be apparent from the description hereinafter given. My invention is herein shown embodied in that 15 type of drive which is characterized by a rotatable member such as a screw shaft driven either directly or indirectly by a prime mover such as the armature shaft of an electric motor, and a driving member 20 adapted to engage a member of the engine to be started, and adapted to be operatively connected with the screw shaft and rotated thereby by means of a screw member threaded 25 on the screw shaft and actuated thereby.

The structure in which my invention is embodied is characterized by the provision of a driving member or pinion loosely mounted on the screw shaft and by a screw member 30 or nut threaded on the screw shaft and adapted in the case of the wholly automatic type herein shown to directly contact such pinion and advance it longitudinally into mesh with the flywheel and to thereupon

35 operatively connect it with the screw shaft for rotary motion by its screw action thereagainst such pinion, and in the case of the combined hand mesh and automatic demesh or so-called semi-automatic type the pinion 40 is advanced longitudinally into mesh with an engine member by hand or foot after which the screw member performs its function of automatically operatively connecting such pinion with the screw shaft for 45 rotary movement. The pinion and the screw member are particularly characterized by being entirely disconnected and physically independent of each other.

In the drawings Fig. 1 is a sectional plan 50 view of a starter system showing a drive in

which my invention is embodied; Fig. 2 a view similar to Fig. 1 but illustrating the pinion and screw member in a separated position with the pinion in its furthest position to the left while normal; Fig. 3 55 a section of the drive showing the position of the parts while driving; Fig. 4 an end elevation of the pinion; Fig. 5 a section on the line 5 of Fig. 4; Fig. 6 an end elevation of the screw member; Fig. 7 a section 60 on the line 7 of Fig. 6; Fig. 8 an end elevation of a sleeve; Fig. 9 a section on the line 9 of Fig. 8; Fig. 10 a section of a modified form of drive; Fig. 11 a section on line 11—11 of Fig. 10; Fig. 12 an elevation of 65 one end of the screw member; Fig. 13 a section on the line 13—13 of Fig. 12; Fig. 14 a section of another modified form of construction; Fig. 15 a section of still another modified form; Fig. 16 a sectional elevation of still another modified form of 70 construction constituting the semi-automatic type; and Fig. 17 a section (on a smaller scale) taken on line 17 of Fig. 16.

For the sake of a clear and definite description of my invention I have selected the particular embodiment illustrated in the drawings without intention of limitation thereto. Moreover while I have shown the direct mounted type and the outboard type 80 of drive, it will be understood that my invention is applicable to the counter-shaft type and also the inboard type of drive.

As herein shown in Figs. 1 to 3 the prime mover which is here an electric motor 1 has 85 an extended armature shaft 2 on which the drive or transmission is mounted and by which it is rotated. A driving head 3 is secured to the armature or driving shaft 2 by the stud 4 and key 5. A screw shaft 90 having a screw threaded portion 6 and also a plain portion 7 is provided with a driven head 8 at its inner end and with a stop nut 9 at its outer end.

The two heads 3 and 8 are drivingly connected by a yielding driving connection which is here a torsion drive spring 10 anchored at its opposite ends respectively to the stud 4 and to the stud 11.

The driving member is here in the form of 100

a pinion 12 having teeth adapted to mesh with the teeth of a member of the engine to be started, such as the teeth 13 of the engine flywheel 14. This pinion has a smooth central bore by which it is loosely mounted on the screw shaft both on the screw threaded portion and plain portion thereof, with the result that this pinion has freedom of movement both rotarily and longitudinally along substantially the entire length of the screw shaft. This pinion is provided on its inner end with a contact or bearing face formed by a ring or flange 15 which may be made separate or integral therewith but preferably made separate for facility in manufacture.

The control or screw member is a nut 16 which is screw threaded upon the threaded portion 6 of the screw shaft and the same is provided at one end with a flange 17 forming a complementary contact or bearing surface to the flange 15. The pinion and nut are wholly disengaged and the pinion is held in normal or home position by a yielding means but is permitted a slight longitudinal movement or lost motion while in home position as indicated by comparison of Figs. 1 and 2, Fig. 1 illustrating the furthest position of the pinion to the right and Fig. 2 its furthest position to the left while in normal position. As shown this yielding means consists of a coiled spring 18 encircling the plain portion of the screw shaft with one end abutting against the stop nut 9 and the other end against a sleeve 19. This sleeve is preferably made of the peculiar formation illustrated wherein it is seen that it is provided at its outer end with a shell or extension 20 fitting over the spring and adapted to entirely encompass the same during the driving position as seen in Fig. 3, and also protect it from being tightly compressed or subjected to the longitudinal pressure of the pinion. This sleeve also has a reduced portion 21 at its inner end over which the bore of the pinion fits as shown in Figs. 2 and 3.

Describing a cycle of operation and starting with the parts in normal position as shown in either Figs. 1 or 2, when the motor is rotated the screw shaft will be correspondingly rotated with the result that the screw member or nut 16 will be advanced longitudinally to the left carrying with it the pinion 12 and advancing it into mesh with the fly wheel, such movement being against the tension of the light spring 18. In this operation the sleeve 19 is likewise moved longitudinally to the left compressing the spring, until the outer end of such sleeve contacts the stop nut whereupon further longitudinal movement of the parts is arrested. However, the screw action on the nut 16 continues and its flange 17 bears forcibly against the flange 15 of the pinion

and thereby binds the latter securely in operative connection with the screw shaft so as to be rotated by the latter. The flywheel is thereupon rotated and when the engine starts on its own power the nut will be automatically relieved from its binding contact with the pinion and will be automatically screwed back upon the screw shaft whereupon the spring 18 will demesh the pinion and restore it to its normal position on the screw shaft.

Referring to the modified form of construction shown in Figs. 10 to 13 I herein provide means for giving a drag to the nut when substantially in contact with the pinion when in driving position so as to assure the longitudinal movement of the nut at this time for the necessary screw action against the pinion for purpose of driving connection between the pinion and the screw shaft. As shown the nut 22 is provided with a transverse opening in which is slidably arranged a plunger 23 spring pressed outwardly from one side by a coiled spring 24 and limited in such projection by the washer 25. The engaging head 26 of the plunger is rounded and is adapted to engage in a recess or recesses 27 in the adjacent contact face of the flange 15 of the pinion. In the event that the nut should rotate with the shaft instead of advancing longitudinally at the time started, the plunger head 26 will engage in one of the recesses 27 and a sufficient drag will thereby be produced to assure the desired screw action.

In Fig. 14 I have illustrated a modified form of construction for the purpose of showing that the spring 18 is not essential. According to this construction the screw shaft has no plain portion but has merely a threaded portion 28. The pinion is advanced into mesh by the nut in the same manner as before and is arrested in its longitudinal advance movements by the stop nut 9. After the engine has started on its own power the pinion is demeshed automatically by the conveyor action of the screw threads 28, it being understood that the pinion having a large smooth bore bears loosely upon the threads which act to convey the pinion to normal position without the provision of any screw threads in such pinion.

By reason of the freedom of the pinion in its mounting and in its rotation, which facilitates the entrance of the pinion teeth between the fly wheel teeth, the possibility of abutment of these teeth is practically eliminated and if by any chance such abutting should occur the pinion would be slightly turned by the screw member to obtain proper register.

In the broader aspect of my invention the pinion need not be mounted directly on the

screw shaft but may be mounted indirectly thereon as seen in Fig. 15, in which the pinion rests upon a forward extension of the screw member, as well as upon the sleeve 19.

- 5 In Fig. 16 I have shown a modified form of construction according to which the pinion or driving member may be shifted by hand or foot instead of automatically, or may be shifted automatically in case of failure of the manual means to work. In this construction the drive proper is the same as that illustrated in Fig. 1 with the exception that the flange of the pinion is increased in diameter so as to provide an annular portion projecting beyond the circular edge of the flange 17 of the screw member or nut 16. In this modified construction a casing 29 is secured in suitable manner to the frame of the motor 1 and the same encloses the drive 10 and the manual shifting means for the pinion. A rod or shaft 30 is mounted in the casing parallel to the armature shaft 2 and adapted to support a sliding sleeve 31. A shifter device 32 is secured to the sleeve 31 and provided with yoke 33 whose ends which may be rounded or provided with rollers 34 are adapted to contact the projecting or annular portion of the flange 15' of the pinion 12. A shifter sleeve 35 is mounted on the sleeve 31 and adapted to move the latter longitudinally to the left with a yielding pressure by reason of the interposed coil spring 36 between the shifter device 32 and the sleeve 35. A shifter yoke 37 secured to the rock shaft 38 which is pivoted in the bracket 39 has its lower or engaging ends 40 cooperating with the shifter sleeve 35. The shaft 38 is rocked by and is connected by means of the arm 41 with a manually or pedally operated plunger 42 normally held in upward or normal position by the coiled spring 43. This plunger is provided with an adjustable projection or screw 44 which when the plunger is depressed is adapted to contact and operate the button 45 of the switch 46 for supplying current to the motor after the pinion 12 has been meshed with the flywheel teeth 13.

Describing the operation of this modified form, when the plunger 42 is depressed the yoke 37 will be rocked in a clockwise direction thereby moving the shifter yoke 33 to the left and moving the pinion 12 longitudinally of the screw shaft and into mesh 55 with the flywheel. Thereupon current is supplied to the motor and the screw shaft rotated whereupon the nut 16 will be advanced longitudinally into contact with the flange 15' of the pinion with the same result 60 in the driving operation as stated in connection with the form shown in Fig. 1. When the operator releases the pressure on the plunger 42 which may be either before or after the engine starts on its own power, 65 the manual shifting means will be restored to normal position by means of the spring 43. When the engine has started on its own power the pinion 12 will be restored to normal position by the spring 18. In the event that the pinion teeth and flywheel teeth 70 should abut end to end the continued depression of the plunger 42 will be taken care of by the spring 36 which will become compressed when the longitudinal shifting movement of the shifter device 32 is arrested at such time. When the screw shaft is rotated by the motor the nut will engage the pinion flange and start to rotate it whereupon full register between the teeth will be obtained and the spring 36 will force 75 the pinion 12 into full mesh whereupon the screw member will follow up the pinion and cooperate therewith in the driving operation as before.

It will be understood that in case the manual means should fail to work for any reason and the button 45 is operated to supply current to the motor, the drive will act as a wholly automatic drive inasmuch as the manual means have been so constructed and arranged as not to preclude such automatic action.

I claim:

1. An engine starter drive including a rotatable shaft, a driving member mounted thereon for longitudinal movement thereof for engagement with a member of the engine to be started, and capable of rotary movement therewith after such engagement, an actuating member mounted for automatic longitudinal movement when such shaft is rotated and for rotary movement therewith when its longitudinal movement is stopped by contact with the driving member, said two members being normally disconnected 100 and free of each other.

2. An engine starter drive including a rotatable shaft, a driving member mounted thereon for longitudinal movement thereof for engagement with a member of the engine to be started, and capable of rotary movement therewith after such engagement, an actuating member mounted for automatic longitudinal movement when such shaft is rotated and for rotary movement 110 therewith when its longitudinal movement is stopped by contact with the driving member, said driving member being loosely mounted on the shaft and having longitudinal movement thereon independent of the actuating member, and such two members being normally disconnected and free of each other.

3. An engine starter drive including a rotatable shaft, a driving member mounted thereon for longitudinal movement thereof for engagement with a member of the engine to be started, and capable of rotary movement therewith after such engagement, an actuating member mounted for auto- 125

matic longitudinal movement when such shaft is rotated and for rotary movement therewith when its longitudinal movement is stopped by contact with the driving member, said two members being normally disconnected and having complementary contact surfaces which are normally inoperative and operative only after engagement between the driving and engine members, 10 whereby the driving member is thereupon drivingly connected with the shaft.

4. An engine starter drive including a rotatable shaft, a driving member mounted thereon for longitudinal movement thereof 15 for engagement with a member of the engine to be started, and capable of rotary movement therewith after such engagement, an actuating member mounted for automatic longitudinal movement when such shaft is 20 rotated and for rotary movement therewith when its longitudinal movement is stopped by contact with the driving member, said shaft having stop means for arresting the longitudinal movement of the driving member 25 in the direction for its engagement with the engine member and said two members being normally free of each other but having complementary contact surfaces which are in operative engagement only after the 30 driving member has been arrested in its longitudinal movement by the stop means.

5. An engine starter drive including a rotatable shaft, a driving member mounted thereon for longitudinal movement thereof 35 for engagement with a member of the engine to be started, and capable of rotary movement therewith after such engagement, an actuating member mounted for automatic longitudinal movement when such shaft is 40 rotated and for rotary movement therewith when its longitudinal movement is stopped by contact with the driving member, said two members being normally free of each other but having contact surfaces which are 45 normally inoperative and operative only after engagement between the driving and engine members, whereupon the driving member is drivingly connected with the shaft.

50 6. An engine starter drive including a rotatable shaft, a driving member mounted thereon for longitudinal movement thereof for engagement with a member of the engine to be started, and for rotary movement therewith after such engagement, and 55 an actuating member mounted for automatic longitudinal movement when such shaft is rotated and for rotary movement therewith when its longitudinal movement is stopped 60 by contact with the driving member, said members having rotary and longitudinal movements independently of each other.

7. An engine starter drive including a rotatable shaft, a driving member mounted 65 thereon for longitudinal movement thereof

for engagement with a member of the engine to be started, and capable of rotary movement therewith after such engagement, an actuating member mounted on the shaft for automatic longitudinal movement thereon when such shaft is rotated and for rotary movement therewith when its longitudinal movement is stopped by contact with the driving member, said two members being normally disconnected and the actuating member having a free longitudinal movement independent of the driving member. 70

8. An engine starter drive including a rotatable screw shaft, a driving member mounted on the screw shaft for longitudinal sliding movement thereof, and an actuating member screw threaded upon such shaft for automatic longitudinal movement when the shaft is rotated, and adapted to engage and rotate the driving member, said driving member being loosely mounted on the shaft and having free longitudinal movements independent of the actuating member. 80

9. An engine starter drive including a rotatable screw shaft, a driving member mounted on the screw shaft for longitudinal sliding movement thereof, and an actuating member screw threaded upon such shaft for automatic longitudinal movement when the shaft is rotated, and adapted to engage and rotate the driving member, said driving member being loosely mounted on the shaft independently of the actuating member and having free longitudinal movements independent of such actuating member, said two members having complementary contact surfaces which are normally inoperative and operative only after engagement between the driving member and the member of the engine to be started. 90

10. An engine starter drive including a rotatable screw shaft having a stop means, an actuating member screw threaded upon such shaft for automatic longitudinal movement when the shaft is rotated, and a driving member mounted for longitudinal sliding movement on the shaft and normally freely movable between the stop means and the actuating member, and independently 100 of the latter but adapted to be engaged and rotated thereby when the driving member is arrested by the stop means and is in engagement with a member of the engine to be started. 105

11. An engine starter drive including a rotatable screw shaft having a stop means, an actuating member screw threaded upon such shaft for automatic longitudinal movement when the shaft is rotated, and a pinion adapted to engage a member of the engine to be started and having a smooth bore receiving such screw shaft and loosely mounted on the screw shaft for longitudinal sliding movement thereon, and normally 120 115 125

- freely movable between the stop means and the actuating member and independently of the latter, but adapted to be clamped therebetween for rotary movement when the actuating member has been moved longitudinally and the pinion has been arrested by the stop means and has engaged the engine member. 65
12. An engine starter drive including a rotatable screw shaft having a stop means, an actuating member screw threaded upon such shaft for automatic longitudinal movement when the shaft is rotated, and a driving member adapted to engage a member of the engine to be started and having a smooth bore receiving such screw shaft and mounted to slide on the screw shaft, said driving member being adapted to be clamped between the stop means and the actuating member and to be thereupon drivingly connected with the shaft, said two members being normally disconnected. 70
13. An engine starter drive including a rotatable screw shaft having a stop means, an actuating member screw threaded upon such shaft for automatic longitudinal movement when the shaft is rotated, and a driving pinion adapted to mesh with a member of the engine to be started and having a smooth bore for sliding movement longitudinally of the shaft, said pinion being freely movable longitudinally independently of the actuating member and adapted to be clamped between the stop means and the actuating member by the screw action of the latter on the screw shaft when rotated, and to be thereupon rotated by such clamping action of the actuating member with the pinion. 75
14. An engine starter drive including a rotatable screw shaft, a nut threaded thereon for free longitudinal movement in both directions on such shaft when the latter is rotated, and a pinion mounted to slide freely on the shaft in the path of movement of the nut in one direction, and, at the limit of movement in such direction adapted to be engaged and drivingly connected with the shaft by the screw action of the nut against its pinion. 80
15. An engine starter drive including a rotatable member, a driving member loosely mounted thereon and adapted to engage a member of the engine to be started, yielding means for normally holding such driving member out of such engagement, and a control member mounted on the rotatable member for automatic longitudinal movement thereon and in its longitudinal movement adapted to contact such driving member and operatively connect it with the rotatable member for rotary movement after said engagement with the engine member, said yielding means consisting of a coiled spring arranged in the path of longitudinal advance movement of the driving member. 85
16. An engine starter drive including a rotatable member, a driving member loosely mounted thereon and adapted to engage a member of the engine to be started, yielding means for normally holding such driving member out of such engagement and a control member mounted on the rotatable member for automatic longitudinal movement thereon and in its longitudinal movement adapted to contact such driving member and operatively connect it with the rotatable member for rotary movement after said engagement with the engine member, said yielding means consisting of a sleeve loosely mounted on the rotatable member in advance of the driving member and tending to resist the longitudinal advance movement thereof, and a spring for backing up said sleeve. 90
17. An engine starter drive including a rotatable member, a driving member loosely mounted thereon and adapted to engage a member of the engine to be started, yielding means for normally holding such driving member out of such engagement and a control member mounted on the rotatable member for automatic longitudinal movement thereon and in its longitudinal movement adapted to contact such driving member and operatively connect it with the rotatable member for rotary movement after said engagement with the engine member, said yielding means consisting of a sleeve loosely mounted on the rotatable member in advance of the driving member and tending to resist the longitudinal advance movement thereof, and a spring for backing up said sleeve. 95
18. An engine starter drive including a rotatable member, a driving member loosely mounted thereon and adapted to engage a member of the engine to be started, yielding means for normally holding such driving member out of such engagement, and a control member mounted on the rotatable member for automatic longitudinal movement thereon and in its longitudinal movement adapted to contact such driving member and operatively connect it with the rotatable member for rotary movement after said engagement with the engine member, said yielding means consisting of a sleeve loosely mounted on the rotatable member in advance of the driving member and tending to resist the longitudinal advance movement thereof, and a spring for backing up said sleeve, said sleeve having a reduced portion and the driving member having a base whose front end fits upon such portion. 100
19. An engine starter drive including a rotatable member, a driving member loosely mounted thereon and adapted to engage a member of the engine to be started, yielding means for normally holding such driving member out of such engagement, and a control member mounted on the rotatable member for automatic longitudinal movement thereon and in its longitudinal movement adapted to contact such driving member and operatively connect it with the rotatable member for rotary movement after said engagement with the engine member. 105
20. An engine starter drive including a rotatable member, a driving member loosely mounted thereon and adapted to engage a member of the engine to be started, yielding means for normally holding such driving member out of such engagement and a control member mounted on the rotatable member for automatic longitudinal movement thereon and in its longitudinal movement adapted to contact such driving member and operatively connect it with the rotatable member for rotary movement after said engagement with the engine member. 110
21. An engine starter drive including a rotatable member, a driving member loosely mounted thereon and adapted to engage a member of the engine to be started, yielding means for normally holding such driving member out of such engagement and a control member mounted on the rotatable member for automatic longitudinal movement thereon and in its longitudinal movement adapted to contact such driving member and operatively connect it with the rotatable member for rotary movement after said engagement with the engine member. 115

ment adapted to contact such driving member and operatively connect it with the rotatable member for rotary movement after said engagement with the engine member, said yielding means consisting of a sleeve loosely mounted on the rotatable member in advance of the driving member and tending to resist the longitudinal advance movement thereof, and a spring for backing up said sleeve, said sleeve having a shell extension fitting over such spring.

20. An engine starter drive including a rotatable shaft having a plain portion and a screw threaded portion, a pinion adapted to engage a member of the engine to be started and having a smooth bore fitting loosely upon said two portions, yielding means for normally holding the pinion on the screw threaded portion, a stop nut at 20 the outer end of such plain portion, and a screw member threaded on such threaded portion and cooperating with the pinion, said yielding means consisting of a sleeve loosely mounted and movable longitudinally up 25 on said plain portion and arranged in the path of longitudinal movement of the pinion, and a spring encircling such plain portion for yieldingly holding such sleeve in an inward position towards the pinion, said 30 sleeve having a shell portion fitting over such spring and also over such stop nut when the sleeve is moved thereagainst by the pinion.

21. An engine starter drive including a rotatable shaft having a plain portion and a screw threaded portion, a pinion adapted to engage a member of the engine to be started and having a smooth bore fitting loosely upon said two portions, yielding 35 means for normally holding the pinion on the screw threaded portion, and a screw member threaded on such threaded portion and adapted to be automatically moved longitudinally by rotation of such shaft and to 40 contact the pinion to operatively connect it with the shaft for rotary movement therewith, said yielding means consisting of a sleeve loosely mounted and movable longitudinally upon said plain portion and arranged in the path of longitudinal movement of the pinion, and a spring encircling 45 such plain portion for yieldingly holding such sleeve in a normal position against said threaded portion.

55. 22. An engine starter drive including a rotatable screw threaded shaft, a driving member loosely mounted thereon and adapted to engage a member of the engine to be started, a screw member threaded on the 60 shaft and adapted to contact and bear against the driving member, and means mounted on one of the members and cooperating with the other member but unattached thereto for imparting a drag to the screw

member to assure longitudinal movement on 65 the shaft.

23. An engine starter drive including a rotatable screw threaded shaft, a driving member loosely mounted thereon and adapted to engage a member of the engine to be 70 started, a screw member threaded on the shaft and adapted to contact and bear against the driving member, and a spring pressed member mounted on the screw member and adapted to yieldingly engage the 75 driving member when in proximity thereto to assure longitudinal movement of the screw member on the shaft and a consequent forcible contact thereof with the driving member.

24. An engine starter drive including a rotatable screw threaded shaft, a driving member loosely mounted thereon and adapted to engage a member of the engine to be 80 started, a screw member threaded on the shaft and adapted to contact and bear against the driving member, said driving member having on one end an annular flange provided with a recess, and said screw member having a face adapted to contact said 85 flange, and a spring pressed device mounted in the screw member and adapted to engage such recess when in proximity thereto.

25. An engine starter drive including a rotatable shaft, a driving member mounted 90 thereon for longitudinal movement thereof for engagement with a member of the engine to be started and capable of rotary movement therewith after such engagement; an actuating member mounted upon and operatively connected with the shaft and capable of longitudinal movement thereof and of rotary movement therewith, and a friction clutch interposed between said driving and actuating members and forming the driving 95 connection between them, such clutch being under substantially no tension when the driving member is in disengaged position.

26. An engine starter drive including a rotatable screw shaft, a pinion loosely mounted thereon and capable of longitudinal movement thereof for engagement with a member of the engine to be started and of rotary movement therewith after such engagement, a screw member threaded upon 100 the screw shaft and capable of longitudinal movement thereof and of rotary movement therewith, and a friction clutch interposed 105 between the pinion and said screw member and forming the driving connection between them, such clutch being under substantially no tension when the driving member is in disengaged position.

27. An engine starter drive including a rotatable shaft, a driving member mounted 110 thereon for longitudinal movement thereof for engagement with a member of the engine to be started and capable of rotary move- 115

ment therewith after such engagement, an actuating member mounted upon and operatively connected with the shaft and capable of longitudinal movement thereof, and of rotary movement therewith, means for arresting said longitudinal movement of the driving member and a friction clutch interposed between the actuating and the driving mem- bers, said clutch being normally inoperative and operative only after engagement between the driving member and the engine member, whereupon the actuating member and the driving member are drivingly connected. 10

WILLIAM L. McGRATH.
